UNITED STATES PATENT OFFICE.

EDWARD A. JOHNSTON, OF STERLING, ILLINOIS, ASSIGNOR TO INTERNATIONAL HARVESTER COMPANY, A CORPORATION OF NEW JERSEY.

CHANGEABLE-SPEED GEARING.

No. 848,609.

Specification of Letters Patent.

Patented Feb. 12, 1907.

Application filed October 4, 1906. Serial No. 337,338.

To all whom it may concern:

Be it known that I, EDWARD A. JOHNSTON, a citizen of the United States, residing at Sterling, in the county of Whiteside and State of Illinois, have invented a new and useful Improvement in a Changeable-Speed Gearing, of which the following is a complete specification.

This invention relates to the gear-transmission for motor-vehicles and means for controlling same, the object being to provide an improved and simple construction of such mechanism and one in which the gears are in constant engagement and the clutch members are operated by means of a single lever.

Referring to the accompanying drawings, Figure 1 represents a side elevation of a complete automobile embodying my improvement. Fig. 2 shows a horizontal section through the gears and casing of the transmission device, taken as indicated by the line 2 2 in Fig. 1. Fig. 3 is a transverse section of the device, taken on the line 3 3 of Fig. 2. Fig. 4 is also a transverse section taken on the line 4 4 of Fig. 2 and is designed to show the construction of the friction-clutch located adjacent to the fly-wheel of the engine. Fig. 5 is a plan of the nest of gears, the casing being shown in section. Fig. 6 represents a rear elevation of the casing and parts adjacent thereto, the view being taken as indicated by the line 6 6 in Fig. 1. Fig. 7 is a plan, partly in section, on the line 7 7 of Fig. 1 and is designed to show the construction of the controlling-lever and its connection with the clutch-shipping spindle. Figs. 8 and 9 represent, respectively, an end and a front elevation of the parts shown in Fig. 6. Fig. 10 is an enlarged detail of the lever-quadrant, and Fig. 11 is a detail of the flanged collar on which are mounted the pawls of the clutch.

In the drawings, 1 designates the body of the automobile, in which is suitably mounted an engine 2, the engine being shown in dotted lines in Fig. 1.

In Fig. 2 is shown the end of the crank-shaft 3 of the engine, and keyed thereto is the fly-wheel 4. A two-part gear-casing 5 is secured by means of the brackets 8 to the body 1, and is therefore fixed in relation to the engine 2. Hollow hubs 5' are formed integral with the casing 5 and project laterally therefrom, the inner hub surrounding but not contacting the end of the crank-shaft 3. A gear

or pinion 6, provided with a long sleeve-like hub 6', fits within the hub 5' and engages also the end of the crank-shaft, as clearly shown in Fig. 2. To the inner end of the pinion-sleeve 6' is secured the driven member of the friction-clutch, which will be hereinafter described. Formed, preferably, integral with the pinion 6 and on the opposite or outer side thereof is the annular-shaped internal toothed rim 6'', which constitutes the driving member of a positive clutch. Subsequent reference will be made to this last-mentioned clutch, and a description thereof will be given.

A gear 7, provided with a long hollow hub 7' and an annular-shaped ratchet-toothed rim 7'', is arranged within the casing 5, the hub 7' of the gear fitting within the hub 5' of the casing. Within the bores of the hubs 6' and 7' of the pinion 6 and gear 7, which are in alinement with each other, as well as with the crank-shaft 3, is received the hollow driving-spindle 9. The inner end of this spindle abuts the end of the crank-shaft 3, while its outer end projects somewhat beyond the ends of the hubs 5' and 7' of the casing 5 and gear 7, respectively, and has fixed to its end the small sprocket-wheel 10. Mounted loosely upon this spindle 9 between the pinion 6 and gear 7 is the reversing-gear 11, provided also with a ratchet-toothed rim 11'. It is therefore evident that as the gears 6, 7, and 11 are mounted loosely on the driving-spindle 9 when caused to rotate they will impart movement to the said driving-spindle, and hence to the driving sprocket-wheel 10, whenever connection is made between the said spindle and gears.

In the casing 5 is also journaled the shaft 12, which extends parallel with the spindle 9. To this shaft are fixed the gear 13, which meshes with and is driven by the pinion 6, and the long pinion 14, which meshes with and drives the gear 7. This connection just described provides the low speed when the gear 7 is clutched to the driving-spindle 9. On the stud-shaft 15 is journaled the idler-pinion 16, which transmits reverse movement to the reverse gear 11 from the pinion 14.

From the arrangement of gears just described it will be seen that the rotation of the pinion 6 will impart movement at a reduced speed in the same direction to the gear 7 and a movement at a reduced speed in a reverse

direction to the gear 11, the pinion 6 and gears 7 and 11 all rotating loosely upon the hollow driving-spindle 9. The means employed for clutching into engagement this driving-spindle with any one of the three gears mounted thereon will now be described.

On the spindle 9 is keyed or otherwise secured the driven double clutch member 17, a detail of which is shown in Fig. 11 and a cross-section thereof in Fig. 3. This clutch member consists simply of a sleeve provided with the end flanges 17' and the heavy central flange 17'', between which are pivotally mounted in relatively reverse order the driving-pawl 18 and 19. These driving-pawls do not differ in construction, but are arranged to drive the coöperating clutch members in opposite directions, the pawls 18 adapted to engage the internal toothed rim 6'' of the gear 6 and the pawls 19 adapted to engage the internal toothed rim 11' of the gear 11. A single clutch member 20, keyed also to the driving-spindle 9 and corresponding in construction to the clutch member 17, has mounted thereon the pawls 21, which are adapted to engage the internal toothed rim 7'' of the gear 7. These pawls terminate each in an inwardly-deflected radially-extending toe *a*, which projects through an opening 17^a in the clutch member 17 and also through a corresponding registering opening 9^a in the driving-spindle 9. A coil-spring 22, fitting in a socket 22' in the pawls 18, 19, and 21 and in recesses in the clutch member 17, operates to hold the outer end of each pawl into engagement with the driving member of the clutch and the toe end *a* of the pawl toward the center of the spindle 9. To positively disengage the pawls 19 from the coöperating clutch members, a longitudinally-movable stem 23, fitting closely within the hollow spindle 9, is employed. This stem 23 is provided with the necks *b* and *c* or portions of the stem of reduced cross-section, into which the toes *a* of the pawls 18, 19, and 21 are forced by the springs 22 to effect the disengagement of the clutch members. These necks *b* and *c* are so disposed that when in the full-line position, as shown in Fig. 2, the neck *b* will register longitudinally with the pawls 19, and the toes *a* thereon will drop into said neck, and thereby result in the engagement of the clutch member 17 and spindle 9 with the gear 11, which is driven through the idler 16, as heretofore explained, and the driving-sprocket 10 will be driven in a reverse direction.

When the neck *c* occupies the position *c*², as it does in first starting, the pawls 21 on the clutch member 20 will in like manner be caused to engage the gear 7 and a lower speed imparted to the sprocket-wheel 10. When the neck *c* is in the position *c*², the neck *b* will occupy the position *b*², and hence the toe *a* of the pawls 18 and 19 will rest on the

top of the stem 23, hold said pawls out of engagement with their coöperating members. When the neck *b* moves from the position *b*² to *b*', it will register with the pawls 18 and permit their engagement with the toothed ratchet-rim 6'' on the pinion 6, while the neck *c* will have moved to the position *c*' and effect the disengagement of the gear 7 from the driving-spindle 9. In this last-described movement the pinion 6 is made to engage direct with the spindle 9 and the high speed is secured. Continued outward movement of the stem 23 will bring the neck *c* from the position *c*' to *c* and the neck *b* from *b*' to *b*, in which position the dogs 19 will engage the gear 11 with the spindle 9 and cause reverse motion, as before described.

In order to frictionally engage and disengage the pinion 6 with the driving-element of the engine, a flange 24 with a lining 25 is formed on the fly-wheel 4, and a spider 26 is fixed to the end of the sleeved hub 6' of said pinion. On two arms of this spider (see Fig. 4) are pivotally mounted the two angle-levers 27, to the outer ends of which are fixed the band-brake 28, encircling the flange 24 and lining 25 thereon of the fly-wheel. The inner ends of the arms 27 lie opposite to each other and near the hub 5' of the casing 5. It will be seen from this construction that an outward movement of the arms 27 will operate to tighten the band 28 and cause the spider and pinion to rotate with the fly-wheel. This outward movement is accomplished by means of the longitudinally-movable grooved collar 29, which engages the hub 5' of the casing. This collar is provided with the two wedge-shaped longitudinally-extending arms 29', which project between the lugs 26' on the spider 26 and are thus made to rotate therewith. The arms 29' are made to move beneath the rollers 27' on the angle-levers 27, and thus tighten or loosen the grip of the band 28 on the flange 24. The springs 28' form a yielding connection between the arms 27 and the said band 28. From the preceding description it is evident that to actuate the positive clutches in the nest of gears longitudinal movement must be imparted to the stem 23, and to actuate the friction-clutch longitudinal movement must be imparted to the collar 29. The mechanism for imparting such movement to these parts will now be described.

A rod 30 extends through the casing 5, engaging the annular groove 29² in the collar 29, by means of the arm 30', and at its outer end projecting through the body of the box 1. On the outer end of this rod is loosely mounted the hand-lever 31, which is provided with the outwardly-projecting arm 31'. On this arm 31' is pivotally mounted the angle-lever 32, engaging at its lower end, by means of the usual fork and groove, the end of the rod 30. On the upper end of the

hand-lever 31 is mounted the secondary lever 33, which connects, through the rod 34, with the angle-lever 32, and in this manner affords means for moving the rod 30 in and out, and thereby engage and disengage the friction-clutch. To actuate the stem 23, an arm 31² is formed integral with the hand-lever 31 and is made to extend rearwardly from the fulcrum thereof. An angle-lever 35, pivoted at 35' on a support 36 and moving in a plane transverse with respect to the plane of movement of the lever 31, engages with the arm 31² above and with a groove 23' in the end of the stem 23. Through this connection movement of the lever 31 on its axis will produce a longitudinal movement of the stem 23, and to regulate the extent of movement required to cause the necks *b* and *c* to register with the desired pawl a quadrant 37 is provided. This quadrant 37 is provided with the notches 37', 37², and 37³ (see Fig. 10) when the lever 31 is in engagement therewith, corresponding, respectively, to low speed, high speed, and reverse. Instead of the usual thumb-latch and adjunctive parts thereof for engaging the particular notch required, the upper arm of the angle-lever 32 is provided with an extension 32', which is adapted to engage any one of the notches 37', 37², or 37³ when the secondary lever 33 is raised to engage the friction-clutch, as heretofore explained.

What I claim as my invention, and desire to secure by Letters Patent, is—

35 1. In a changeable-speed gearing, in combination, a hollow driving-spindle, a plurality of clutch members secured thereto, a corresponding number of gears, loosely mounted thereon and having coöperating clutch members in connection therewith, a driving element adapted to frictionally engage one of said gears, a gear connection extending between the gear which connects with the driving element and the remaining gears, and means for engaging and disengaging said clutch members.

2. In a changeable-speed gearing, in combination, a hollow driving-spindle, a plurality of clutch members secured thereto, a corresponding number of gears loosely mounted thereon and having coöperating clutch members in connection therewith, a casing inclosing said gears and forming a journal-support therefor, a driving element adapted to frictionally engage one of said gears, a gear connection extending between the gear which connects with the driving element and the remaining gears, and a longitudinally-movable stem located within said hollow driving-spindle for engaging and disengaging said clutch members.

3. In a changeable-speed gearing, in combination, a hollow driving-spindle, a plurality of positive clutch members secured thereto, a corresponding number of gears loosely

mounted thereon and having coöperating clutch members in connection therewith, a driving element, a friction-clutch interposed between said driving element and one of said gears on the driving-spindle, a gear connection extending between the gear which connects with the friction-clutch and the remaining gears and single means for actuating both the positive and friction clutch members.

4. In a changeable-speed gearing, in combination, a hollow driving-spindle, positive clutch members fixed thereto, three gears loosely mounted on said spindle and each provided with an internal ratchet-toothed rim adapted to coöperate with said clutch members, a driving element, a friction-clutch interposed between said driving element and one of said gears on the driving-spindle, a forward and a reverse gear connection extending between the gear which connects with the friction-clutch and the remaining gears, a longitudinally-moving stem and rod for actuating respectively the positive clutch members and the friction-clutch, and a single lever for controlling same.

5. In a changeable-speed gearing, in combination, a hollow driving-spindle, positive clutch members fixed to said spindle and provided with pawls pivotally mounted thereon, three gears loosely mounted on said spindle and each provided with an internal ratchet-toothed rim adapted to coöperate with said clutch members, a driving element, a friction-clutch interposed between said driving element and one of said gears on the driving-spindle, a forward and a reverse gear connection extending between the gear which connects with the friction-clutch and the remaining gears, a longitudinally-moving stem provided with necks or portions of reduced cross-section and adapted to actuate the pawls of said positive clutches, a longitudinally-moving rod for actuating the friction-clutch, and single means for controlling both the rod and stem.

6. In a changeable-speed gearing, in combination, a hollow driving-spindle, a plurality of positive clutch members fixed thereto, a corresponding number of gears loosely mounted thereon and having coöperating clutch members in connection therewith, a driving element, a friction-clutch adapted to frictionally engage said driving element with one of said gears on the spindle, a gear connection extending between the last-mentioned gear and the remaining gears on said spindle, separate longitudinally-movable means for actuating the friction-clutch and the several positive clutch members, and a single lever for controlling the clutch-actuating means.
